UNITED STATES PATENT OFFICE.

ALBERT F. EELLS, OF ROCHESTER, NEW YORK, ASSIGNOR OF ONE-HALF TO AMERICAN LOCOMOTIVE COMPANY, OF NEW YORK, N. Y., A CORPORATION OF NEW YORK.

STOCKLESS ANCHOR.

Application filed December 4, 1923, Serial No. 678,459. Renewed September 28, 1925.

To all whom it may concern:

Be it known that I, ALBERT F. EELLS, a citizen of the United States, residing at Rochester, in the county of Monroe and 5 State of New York, have invented certain new and useful Improvements in Stockless Anchors, of which the following is a specification.

This invention relates to certain new and 10 useful improvements in stockless anchors, and it has for its object among others to provide an anchor of this general type which shall be capable of penetrating the sea bottom to a greater depth thereby developing greater resistance. I also provide 15 means whereby the anchor is prevented from capsizing, and also make provision for the ready and clear passage of the sea bottom over the top of the anchor as it is drawn into the sand, mud, or sea bottom, of 20 whatever nature the latter may be.

Other objects and advantages of the 25 present invention will hereinafter appear, and the novel features thereof will be specifically pointed out in the appended claims.

The invention is clearly illustrated in the accompanying drawings, which, with the numerals of reference marked thereon, form a part of this specification, and in which 30 Figure 1 is a plan view of my improved anchor.

Figure 2 is a perspective view thereof.

Like numerals of reference indicate like parts in the different views.

I accomplish the above-outlined objects, 35 as well as others, by the construction shown in the drawings, in which 1 designates the head of the anchor and 2 the shank pivotally mounted therein in any suitable manner.

40 The side members or webs 3 projecting from the centre of the head are flat as shown and each carries a fluke 4, each fluke being thick on the inner side as seen at 5 and thin on the outer side as seen best in Figure 2. 45 The inner face of each fluke is outwardly tapered as seen at 7, and also tapered as to thickness as will be readily understood from Figure 2.

In order to insure that the anchor shall 50 penetrate to a maximum depth in the sea bottom and to remove all obstruction from the sea bottom and to provide a clear passage for the same over the top of the anchor I remove all projecting obstructions between

55 the centre of the head and the flukes, and

taper the inner faces of the said flukes outwardly so that there shall be no impediment to the passage of the sea bottom between the flukes as the anchor is drawn into the sand, mud, or sea bottom. As seen in 60 Figure 2 the face of the side portions 3 is tapered at 8 and the rear ends of the flukes at the outer ends of the said side portions 3 are provided with the portions 9 which extend at right angles to the side portions 3 65 and have their inner faces rounded or tapered as seen at 10, there being projections 11 extending lengthwise of the flukes, the forward ends being brought to a cutting edge as seen at 12. The metal at the inner 70 faces of the portions 9 is removed as seen at 13 so as to leave no obstruction to the passage of the sea bottom. The projections 11 serve to steady the head of the anchor in the hawse pipe and secure it firmly in place, 75 on the ship's bow.

The extension of the projections 11 lengthwise instead of crosswise not only provides the greater passage for the flow of the sea bottom but also serve to tilt the 80 flukes downward so they take a better hold in the sea bottom. Furthermore, these portions 9 and the cutting edges serve to right the anchor should there be a tendency to pull more on the one fluke than on the 85 other which would tend to penetrate the said fluke deeper into the sea bottom, and this would tend to raise the other fluke, and thus cause the anchor to capsize.

Modifications in detail may be resorted to 90 without departing from the spirit of the invention or sacrificing any of its advantages.

What is claimed as new is:—

1. A stockless anchor having its flukes 95 provided with longitudinally extended projections at the outer edges thereof, and webs between the flukes.

2. A stockless anchor having its flukes provided with longitudinally extended projections at the outer edges thereof, and webs 100 between the flukes, the inner sides of the flukes being thicker than the outer sides.

3. A stockless anchor having its flukes tapered toward their forward ends and also 105 tapered from their inner edges outwardly and their outer faces formed with upwardly-extended portions disposed lengthwise of the flukes.

4. A stockless anchor having flukes pro- 110

vided with perpendicularly-disposed pro-
jections elongated in the direction of their
length, the upper and lower faces of said
projections being formed with sharpened
5 forward edges.

5. A stockless anchor having flukes pro-
vided with perpendicularly-disposed pro-
jections elongated in the direction of their
length, the upper and lower faces of said
10 projections being formed with sharpened
forward edges and the inner faces being in-
clined to avoid obstruction of the sea bot-
tom between the flukes.

6. A stockless anchor having its flukes
tapered toward their forward ends and also 15
tapered from their inner edges outwardly,
a shank socket, a shank pivoted in the
socket, and webs forming the only connec-
tion between the flukes and the socket, the
greatest thickness of the webs being sub-
stantially the same as the greatest thickness
of the flukes.

In testimony whereof I affix my signa-
ture.

ALBERT F. EELLS.
